UNITED STATES PATENT OFFICE

DAVID B. HANNA, OF PARK RIDGE, ILLINOIS, ASSIGNOR TO AMERICAN CONCRETE PRODUCTS CO., A CORPORATION OF ILLINOIS

DESIGN FOR A LAMP

Application filed December 31, 1928. Serial No. 29,463. Term of patent 7 years

To all whom it may concern:

Be it known that I, DAVID B. HANNA, a citizen of the United States, residing at Park Ridge, in the county of Cook and State of Illinois, have invented a new and original and ornamental Design for Lamps, of which the following is a specification, reference being had to the accompanying drawing forming a part thereof, which is a side elevation in perspective of a lamp, showing my new design.

I claim:

The ornamental design for a lamp as shown.

In testimony whereof I have signed my name to this specification.

DAVID B. HANNA.
